UNITED STATES PATENT OFFICE.

JAMES H. BEVINGTON, OF BELLEVUE, ASSIGNOR TO THE BEVINGTON SIGNAL COMPANY, OF FOSTORIA, OHIO.

RAILWAY-TORPEDO.

SPECIFICATION forming part of Letters Patent No. 375,254, dated December 20, 1887.

Application filed May 10, 1887. Serial No. 237,737. (No model.)

To all whom it may concern:

Be it known that I, JAMES H. BEVINGTON, a citizen of the United States, residing at Bellevue, in the county of Huron and State of Ohio, have invented certain new and useful Improvements in Railroad Torpedoes for Signaling Purposes, of which the following is a specification.

This invention relates to a torpedo constructed of a suitable size and adapted to be placed upon a railway-track and fastened thereto, as will be hereinafter described, for the purpose of signaling to engineers of passing trains that there is danger ahead. They may also be employed to give notification to switchmen or to station-men or passers-by that a train that has been standing still has just been started.

The invention consists in the present instance of a metallic casing provided with a binding-strap soldered or otherwise suitably attached to the under side of the metal casing, the said casing forming an envelope for an explosive compound located within it.

The invention also consists of the manner of attaching the two halves or plates of the casing so as to avoid the possibility of any explosion while the sealing operation is taking place.

Other points of novelty will be hereinafter referred to, and pointed out in the claim.

Referring to the accompanying drawings, which form a part of this specification, Figure 1 is a plan view of the completed article. Fig. 2 is a plan view of the inside of the torpedo, the upper part and the explosive compound being removed. Fig. 3 is a longitudinal section of the torpedo.

In the drawings, A represents the lower portion or half of the metallic casing, and is provided with a centrally-located depression or recess, V, in which is set a flexible metallic band, C, which is secured to the bottom A by means of soldering, as shown at D. This metallic band is the binder which secures it to the rail of the railroad, as shown in Fig. 3, the railroad-rail being represented at R.

In Fig. 3 also is shown the explosive compound E, which is inclosed within the casing and sealed therein and will explode when the wheel of the locomotive or car passes over it.

In Fig. 1 and 3 is shown the bottom of the casing having a flange or wing, F, which extends upwardly, as shown. Within this lower casing I arrange the upper half or part of the casing G, which upper portion is provided with a flange, H, fitting down into the lower portion of the casing, and over which the flange F of the said portion is adapted to be folded, for the purpose of securing the parts together and confining the explosive compound E within its proper bounds.

In Fig. 2 I show the bottom of the casing, and have indicated in dark lines L a certain quantity of paint or varnish, which corresponds with the size of the flanges before mentioned, and it is placed there for the following purpose: When the explosive compound is placed within the casing and the two parts are pressed together, the flange upon the upper half of the casing will fit down into the lower half and will come in contact with the moist paint or varnish aforesaid. Then the flange is pressed downwardly and inwardly and assumes the position shown in Fig. 3. This binds the two halves of the torpedo together and confines the explosive compound within the casing. When the pressure is applied, as before stated, the moist paint will serve to dampen any of the explosive compound that has got between the flanges, thus preventing any premature explosion when the parts have been thus pressed together. I cover the whole with a suitable waterproofing material, which may be either paint, varnish, or other suitable material.

I also make my improved torpedo in the shape of a wedge, as shown in Fig. 3, so that the locomotive-wheel or car-wheel can easily mount upon it, thus avoiding the danger of it being thrown from the track. This construction has proved of great advantage, and is now in commercial use. The peculiar construction of the torpedo, with the two beveled surfaces slanting downward from the top of the torpedo, said surfaces being flat, adds greatly to the value of the article, inasmuch as the wheel as it comes in contact with the broad flat portion easily mounts thereon, and will not tend to throw the torpedo from the track, as is the case when the said torpedo is

circular in shape. These latter forms have been found to be useless. The central depression in the lower surface of the torpedo affords means for embedding the flexible metallic binding-strap, so that the bottom of the torpedo can seat on the rail and will not be liable to rock from side to side, as would be the case if it were not properly embedded. This construction is also superior to the torpedo having to the strap formed integrally with the metallic casing, for many important reasons.

Having thus described my invention, what I claim as new therein, and desire to secure by Letters Patent, is—

A railway-torpedo having a metallic casing 15 inclosing the explosive compound, the upper part of the casing fitting within the lower part and provided with a flange, as shown, the lower half having paint or varnish placed upon it where the flange of the upper half seats, and 20 also having a flange which fits over the flange of the upper half and secures it in position, all constructed substantially as and for the purposes set forth.

JAMES H. BEVINGTON.
